SEWING MACHINE

Clifford Roberts, Winchester, and John M. Whelton, Peabody, Mass., assignors to United Shoe Machinery Corporation, Paterson, N. J., a corporation of New Jersey

Application September 28, 1935, Serial No. 42,656

7 Claims. (Cl. 112—45)

The present invention relates to improvements in shoe machines, and more particularly to machines for sewing the margins of shoe soles in which there is a concealed channel having a flap beneath which the seam is formed. The invention is herein shown as embodied in a sole sewing machine of the so-called McKay type having a straight hook needle and a work support which consists of a rotatable horn arranged to extend within the shoe, and provided at its tip with a needle threading device for laying the thread in the hook of the needle.

In stitching the outsole of a shoe having a seam concealing flap, it is necessary to raise the flap in advance of the point of operation of the stitch forming devices, and to hold it in raised position beyond the point where the stitches are completed. To do this, it is customary to provide a plow-shaped turning tool more or less elongated in the line of feed which acts directly on the flap. With such an arrangement, the space about the point of operation of the stitch forming devices is not only crowded, but the elongated contact of the flap turning tool with the work renders manipulation of the work difficult, particularly when turning the shoe about the toe.

The object of the present invention is to provide novel and improved means for opening the channel beneath a seam concealing flap of a shoe sole in advance of the point of operation of a sewing or other machine to permit feeding and other work manipulating movements to be effected with comparative ease.

With this object in view the features of the present invention include the provision of means, in a machine for operating upon a shoe sole having a seam concealing channel, to raise the flap covering the channel in advance of the operation of the operating devices by a jet of compressed air directed against the work in the proper direction. With the use of an air jet, elongated contact with the work, as occurs with the use of a special flap turning tool is avoided. The air jet being deflected by the flap and forced along the flap towards the oncoming work as it is fed to raise it into proper position. In applying the invention to a sewing machine as herein described, a tubular conductor for directing the air jet against the work is mounted on the presser foot of the machine, and preferably there is provided a valve for shutting off the supply of air to the conductor while the machine is stopped.

Other features of the present invention consist of certain constructions, combinations and

arrangements of parts, the advantages of which will be apparent from the following description.

In the drawings illustrating the invention in its preferred form, Fig. 1 is a view in side elevation of the upper portion, including the stitch forming and work feeding devices, of a sewing machine embodying the features of the invention; Fig. 2 is a view in front elevation on a somewhat larger scale, of a portion of the stitch forming and work feeding devices with the work in operating position in the machine; Fig. 3 is a view on a still further enlarged scale, partly in section illustrating the operation of the air jet in raising the channel flap of a shoe; and Fig. 4 is a plan view on the same scale as Fig. 3 taken just above the work showing the lower ends of certain of the stitch forming devices in section.

The machine illustrated in the drawings, comprises a straight hook needle 10, a rotary work supporting horn 12, a rotary shuttle 14, a presser foot 16, a feed point 18, a loop spreader 20, and other stitch forming devices constructed and arranged to operate in the manner described in U. S. patent to Bernard T. Leveque No. 1,885,927 granted November 1, 1932.

To operate the machine on a shoe sole, such as indicated at 22 having a seam concealing channel with a flap 24, it is necessary to raise the flap into an upright position as illustrated in Figs. 3 and 4, in order that the stitch forming devices may act properly. The channel is usually formed by making a continuous cut extending inwardly from or near the margin of the sole and increasing in thickness from the margin so that frequently there is considerable resistance offered against raising the flap when bent sharply at its root, it being desirable to form the seam as close as possible to the apex of the angle between the flap and the sole. The pressure against the work guiding devices of the machine required to raise the flap properly may cause improper operation of the machine or produce other undesirable effects.

In order that the seam may be formed close to the apex of the channel cut, in the embodiment of the present invention, a jet of air under pressure is directed against the flap, so that after being deflected by the flap, the air will flow along the channel to raise the flap at either side and particularly in advance of the point of operation of the stitch forming devices. As the raised portion of the flap approaches the outlet of the jet, it need be raised only a small additional amount and maintained in raised position by the side surface of the presser foot, which in the present

machine acts as a work guiding member. The pressure on the presser foot is, therefore, less than would be required to raise the flap without the jet and the flap is raised a greater distance 5 at either side than is otherwise possible with a guiding member of a dimension in the line of feed as narrow as the presser foot.

The air is provided for the jet by a tubular conductor 26 having its outlet, indicated at 28, 10 in the side of the presser foot. The lower end of the presser foot is formed with a work gripping surface 30, the rear side surface past which the flap 24 moves being somewhat rounded to reduce the drag. The tubular conductor 26 is secured 15 by a suitable clamp 32 attached to the presser foot above the work, and the lower end of the tubular member passes horizontally through the presser foot so that the conductor is on the opposite side from the flap.

20 After the seam is completed and before the machine is again started, the supply of air, which may be from any suitable source, is cut off. Before sewing is started, the work is moved into proper operating position with stitch-forming 25 devices and the flap 24 raised by engagement with the side of the presser foot. As soon as the machine is started, air is permitted to flow through the conductor 26 by opening a valve 34 connected with the conductor through a flexible tubing 36, 30 the inlet to the valve being at 38.

To operate the valve in starting the machine, it is connected with the driving and stopping mechanism of the machine under the control of a treadle operated rod 40. As in the machine 35 of the patent above referred to, this rod is connected at its upper end with an arm 42 secured to one end of a horizontal shaft 44 extending across the machine. The other end of the shaft has fixed to it an arm 46 pivotally connected at 40 its outer end with a valve operating rod 48. When the treadle rod is depressed in starting the machine, the operating rod 48 is moved downwardly to open the valve and cause the jet to be started.

The jet is then directed against the flap and 45 due to the shape of the lower end of the presser foot, the air is caused to flow into the crevice and along the flap as it is fed, thereby raising the flap considerably in advance of the jet. To accentuate this result, the edge of the presser foot 50 first engaged by the flap and past which the jet escapes is cut back or beveled, as indicated in Figs. 3 and 4, permitting the greater portion of air to escape in the desired direction. Once having been raised, the flap is held in raised position 55 by the presser foot until the stitch-forming devices have operated, after which the flap may be bent back into its original position, concealing the stitches in the usual manner.

The invention having been thus described, 60 what is claimed is:

1. A shoe machine for operating upon work provided with a seam concealing flap having, in combination, a work support, suitable devices for operating on the work and means for directing 65 a jet of air under pressure against the work to raise the flap for the operating devices.

2. A sewing machine for operating upon work provided with a seam concealing flap having, in combination, a work support, a presser foot, stitch forming devices acting on the work between the work support and presser foot, and a tubular conductor mounted on the presser foot for directing a jet of air under pressure against the work to raise the flap in advance of the point of operation of the stitch forming devices. 5

3. A sewing machine for operating upon work 10 provided with a seam concealing flap having, in combination, stitch forming devices, a work support, a presser foot engaging the work beneath the flap in advance of the point of operation of the stitch forming devices, and means comprising 15 a tubular conductor for directing a jet of air under pressure against the flap to assist the presser foot in raising the flap.

4. A sewing machine for operating upon work provided with a seam concealing flap having, in 20 combination, a work support, a presser foot, stitch forming devices acting on the work between the work support and presser foot, means comprising 25 a tubular conductor for directing a jet of air under pressure against the work to raise the flap in advance of the point of operation of the stitch forming devices, and a valve on the machine for cutting off the flow of air through the conductor when the machine is stopped.

5. A sewing machine for operating upon work 30 provided with a seam concealing flap having, in combination, a work support, a presser foot, stitch forming devices acting on the work between the work support and presser foot, means comprising 35 a tubular conductor for directing a jet of air under pressure against the work to raise the flap in advance of the point of operation of the stitch forming devices, a valve on the machine for cutting off the flow of air through the conductor, and connections including a 40 treadle operated rod for actuating the valve.

6. A sewing machine for operating upon work provided with a seam concealing flap having, in combination, a needle, a work support, a presser foot having a gripping surface to engage the 45 channel beneath the flap in advance of the point of operation of the needle and having a side surface with a bevelled edge to assist in holding the flap raised as it is fed past the needle, and a tubular conductor on the presser foot for directing 50 a jet of air under pressure between the bevelled edge of the pressed foot and flap towards the advancing flap to raise the flap for entrance of the presser foot.

7. A sewing machine of the McKay type for operating upon work provided with a seam concealing flap having, in combination, a straight hook needle, a rotary work supporting horn, a presser foot, a feed point acting on the side of the work engaged by the presser foot to feed the work, and 60 means comprising a tubular conductor for directing a jet of air under pressure against the work to raise the flap in advance of the point of operation of the needle. 65
